CLAIM

The ornamental design for a collapsible motorized utility cart, as shown and described.

DESCRIPTION

FIG. 1 is a right side and rear perspective view of a collapsible motorized utility cart showing my new design, the broken lines are for illustrative purposes only and form no part of the claimed design;
FIG. 2 is a left side elevational view thereof;
FIG. 3 is a top plan view thereof;
FIG. 4 is a front elevational view thereof; and,
FIG. 5 is a side elevational view thereof showing the cart in a collapsed condition.

FIG. 1

FIG. 3

FIG. 4

FIG. 2

FIG. 5
